(57) CLAIM

The ornamental design for a backpack, as shown and described.

DESCRIPTION

FIG. 1 is a front perspective view of a backpack being worn by a runner;

FIG. 2 is a rear, side perspective view of the backpack of FIG. 1;

FIG. 3 is a rear view of the backpack of FIG. 1;

FIG. 4 is a front view of the backpack of FIG. 1;

FIG. 5 is a first side view of the backpack of FIG. 1;

FIG. 6 is a second side view of the backpack of FIG. 1;

FIG. 7 is a top view of the backpack of FIG. 1; and,

FIG. 8 is a bottom view of the backpack of FIG. 1.

The ornamental design that is claimed is shown in solid lines in the drawings. The dashed lines shown in FIGS. 1 through 8 are included for the purpose of illustrating environmental elements only and form no part of the claimed design.
